UNITED STATES PATENT OFFICE

2,500,649

FASTENER FOR WRISTBANDS

Andrew Szeglin, Hempstead, N. Y., assignor to
Swiss Radium & Dial Painting Co., Inc., New
York, N. Y.

Application June 12, 1948, Serial No. 32,683

4 Claims. (Cl. 24—71)

1

This invention relates to snap fasteners for wrist watches, bracelets and the like.

It is an object of the present invention to provide a fastener which is adjustable to accommodate the different size wrists of individuals and wherein the wrist watch or bracelet can be worn in a loose manner or tight manner depending upon the adjustment of the fastener and wherein the slide serves as a means for the securing of the foldable parts of the fastener together, the outward movement of the slide being necessary to a given amount in order that the parts can be separated and folded from one another and wherein the slide can be locked in any one of several different locations to which the same has been adjusted and the distances between these locations being small.

Other objects of the present invention are to provide a fastener for wrist watches, bracelets and the like which is adjustable and wherein the slide serves as the locking device for the parts when they are folded together, which is of simple construction, easy to adjust, inexpensive to manufacture, of pleasing appearance, compact and durable and efficient in operation.

For other objects and for a better understanding of the invention, reference may be had to the following detailed description taken in connection with the accompanying drawing, in which

Fig. 1 is a perspective view of a wrist watch having the adjustable fastener of the present invention in its band.

Fig. 2 is a perspective view of the fastener looking upon the outer part and in the end through which the slide is adjusted but with the slide retracted.

Fig. 3 is a perspective view similar to Fig. 2 of the fastener but with the slide extended or adjusted.

Fig. 4 is a perspective view of the fastener with the parts separated from one another and with the slide in its extended position and released from the inner part.

Fig. 5 is a longitudinal sectional view of the parts with the slide extended and as viewed generally on line 5—5 of Fig. 7.

Fig. 6 is a perspective view of the parts folded outwardly from one another and extended in chain fashion.

Fig. 7 is a fragmentary and plan view looking

2

into the slide and outer part containing the same.

Figs. 8 and 9 are respectively transverse sections taken respectively on line 8—8 of Fig. 2 and line 9—9 of Fig. 3.

Referring now to the figures, 15 represents a wrist watch to the opposite ends of which are connected the ends of a wrist band 16 containing a foldable snap fastener 17 embodying the features of the present invention. The fastener 17 comprises an inner part 18 of arcuate shape, a connecting intermediate part 19 pivotally connected to one end of the inner part 18 and pivotally connected at its other end to an outer part 21. Within the outer part 21 is an adjustable slide 22 having loop or sleeve formations 23 adapted to receive a pin 24 for the connection of the links of the wrist band 16 thereto. The slide 22 can be extended to any one of several positions out of the outer part 21 and retained in those positions. The outer part has at one end or the end out of which the slide is adjusted, an inwardly bent projection 25 adapted to register with any one of a plurality of notches 26 for retaining the slide in the location to which it has been adjusted. The slide is slit as indicated at 27 to provide a central spring portion 28 containing the notches 26. This spring portion extends substantially throughout the length of the slide 22. This portion has a thumb nail projection 29 by which the portion can be inwardly bent to free the projection 25 of one of the notches whereby to permit the slide to be moved outwardly a given amount to locate the projection 25 in another notch.

At one location in the central portion 28 and inwardly of the notches is an elongated notch or groove 31 into which the projection 25 is extended when the slide is pulled out beyond the notches 26 and whereby the slide will be released from the outer part 21 so that the outer part can then be separated from the slide. The slide has at its opposite sides upstanding flanges 32 bent so that the slide can be secured against upward displacement from upwardly and inwardly bent flanges 33 of the outer fastener part 21. The flange 32 is also bent and formed to pass beneath lips 34 of a downwardly and inwardly bent flange 35 of the inner part 18, Figs. 6 and 8. As long as the slide 22 is well within the parts

and still connected through the notches 26 with the central portion 28, the inner part will be locked to the outer part through the slide in the manner just described. As soon as the slide has been moved so the projection is in the rear end of the elongated notch or groove 31, the flanges 32 of the slide will be released from the lips 34 of the inner part 18 and the inner part will no longer be connected with the outer part through the slide intermediary.

It will be apparent that while the slide 22 is adjusted so that the projection 25 is in the notches 26 that the parts will remain secured together and that the band will be in effect longer than if the slide is fully extended inwardly to the position as shown in Fig. 2 with the thumb nail portion engaging with the projection 25.

The intermediate part 19 is hinged between flanges 33 of the outer part 21 by a pin 36. The intermediate part 19 is pivotally connected to the part 18 by a pin 37. The inner part 18 has a sleeve formation 38 by which any of the links of the band portion may be connected.

The several parts of the fastener form, when closed upon one another, a sleeve-like assembly or structure which receives the slide 22 and which has an abutment 25 adapted to cooperate with the several notches 26 of the slide to hold the slide in its adjusted position relative to the sleeve assembly. The slide has the central portion 28 which has to be flexed in order to finally release the last notch 31 from the abutment 25 and for the purpose of removing the slide from the assembly. This flexing cannot be effected until pin 24 has been pulled. When the pin 24 is removed, the band 16 can be released from the slide and the slide can accordingly be released from the sleeve-like assembly or folded parts by simply flexing the central portion to release the last notch 31 thereof.

It will be apparent that the fastener can be adjusted to different lengths so that the wrist band can accommodate the different size arms or can be adjusted to be worn loose or tight as the wearer may desire.

This application provides subject-matter similar to my co-pending application, Serial No. 32,682, filed simultaneously herewith, but the claims hereof are to be directed to the present specific arrangement of a slide part having a series of notches adapted to cooperate with a projection on another part to hold the slide part in an adjusted position and to the use of the securing pin 24 to prevent the full flexure of the central portion 28 while effecting the adjustment to the different notch formations but upon removal thereof allowing the full flexure and the final disengagement of the slide part from the other parts.

While various changes may be made in the detail construction, it shall be understood that such changes shall be within the spirit and scope of the present invention as defined by the appended claims.

I claim:

1. A foldable adjustable slide fastener for bracelets, watch bands and the like comprising parts hinged together and adapted to be folded one upon the other to be fastened, a slide part adjustable in one of the hinged parts, means associated with the parts for holding the same in folded coupled relationship, said slide having two slits and providing for a central portion which may be flexed, said central portion having a projection thereon, said one part in which the slide

part is adjustable having a projection adapted to cooperate with the projection of the slide part to normally prevent the separation of the slide part from the one part, fastening means on the free end of the slide adapted for the attachment of the bracelet part or band therewith, said fastening means including a securing element when in place adapted to normally prevent the flexure of the central portion whereby disengagement of the slide part from the hinged parts is prevented unless the securing element of the fastening means for the attachment of the band is removed, said central portion having a series of notched formations adapted to receive the projection of the one part whereby the slide part can be adjusted and retained in any one of several positions, said securing element being adapted to permit the flexure of the central portion except for the disengagement of the notch formation at the inner end of the central portion by requiring the full removal of the securing element to permit the final disengagement of the slide part from the hinged parts.

2. An adjustable slide fastener device for bracelets, watch bands and the like comprising a sleeve-like assembly, a slide part adjustable in said assembly, said slide having a central portion adapted to be flexed and said sleeve assembly having an abutment thereon, said central portion having an abutment adapted to cooperate with the abutment on the sleeve assembly to normally prevent the disengagement of the slide from the sleeve assembly, an element releasably connected to the free end of the slide for the attachment thereto of a band part, said central portion projecting over the securing element so that the flexing of the central portion will normally be prevented and only adapted to be made upon the securing element being removed, said central portion having a series of notches adapted to receive the abutment of the sleeve assembly whereby the slide can be adjusted and retained in any one of several positions, said securing element adapted to permit the flexure of the central portion to permit the adjustment of the slide through the several notches except for the disengagement of the notch formation or abutment at the inner end of the central portion.

3. A foldable adjustable slide fastener for bracelets, watch bands and the like comprising parts hinged together and adapted to be folded one upon the other to be fastened, a slide part adjustable in one of the hinged parts, means associated with the parts for holding the same in folded coupled relationship, said slide having two slits and providing for a central portion which may be flexed, said central portion having a projection thereon, said one part in which the slide part is adjustable having a projection adapted to cooperate with the projection of the slide part to normally prevent the separation of the slide part from the one part, fastening means on the free end of the central portion of the slide adapted for the attachment of the bracelet part or band therewith, said fastening means including a securing element when in place adapted to normally prevent the flexure of the central portion whereby disengagement of the slide part from the hinged parts is prevented unless the securing element of the fastening means for the attachment of the band is removed.

4. An adjustable slide fastener device for bracelets, watch bands and the like comprising a sleeve-like assembly having an abutment therein, a slide adjustable within the sleeve-like as-

sembly and having an abutment adapted to cooperate with the abutment of the assembly to normally limit the movement of the slide within the assembly and to prevent the disengagement of the slide from the assembly, said slide part having a central portion adapted to be flexed to release the abutments from each other to permit the disengagement of the slide from the sleeve-like assembly, a securing element releasably connected to the slide and adapted to fix a band to the slide, said central portion of the slide extending over the securing element whereby to prevent the flexure of the central portion and the release of the slide from the sleeve assembly

so long as the securing element is in place upon the slide.
